HEATER CONTROL

Arthur R. Collins, Park Ridge, Ill., assignor to
 Stewart-Warner Corporation, Chicago, Ill., a
 corporation of Virginia

Application February 27, 1946, Serial No. 650,600

3 Claims. (CL 236—68)

1
 The present invention relates to heater controls and is, more particularly, directed to a control system adapted for use with a heater of the general type disclosed in the patents to Theodore Y. Korsgren 2,482,552, issued September 20, 1949, and Frank A. Ryder 2,502,345, issued March 28, 1950. It will be appreciated, however, that although the control system of the present invention is particularly adapted for use with heaters of this type, it is not limited to such use but is of more general application.

It is an object of the present invention to provide a control system for a heater which will modulate the output of the heater according to demand conditions.

An additional object of the present invention is to provide a novel heater control circuit and mechanism which operates the heater at a low rate of heat output unless greater heat output is necessary to satisfy the prevailing conditions.

Yet another object of the present invention is to provide an improved heater control arrangement which prevents the heater from cycling on and off excepting under extremely mild weather conditions.

Still another object of the present invention is to accomplish all of the above with a mechanism of low cost and which is safe and reliable in operation.

Other objects and advantages will become apparent from the following description of a preferred embodiment of my invention which is illustrated in the accompanying drawings.

In the drawings, in which similar characters of reference are used to indicate similar parts in both the figures:

Fig. 1 is a diagrammatic representation of a heater of the type disclosed in the previously referred to copending applications; while

Fig. 2 is a diagrammatic representation of the control system for use therewith which illustrates the present invention, including both mechanical and electrical components.

As explained in the previously referred to copending applications, the heating system with which the control arrangement of the present invention is particularly adapted for use is comprised of a variable speed electric motor 10 which drives a ventilating air blower 12 and a combustion air blower 14. The combustion air blower receives its air through a duct 16 which leads preferably to the outside of the building to be heated. The ventilating air blower 12 receives its air through an opening 18 which may be in the space to be heated. Air from these two

2
 sources, that is, the ventilating air blower 12 and the combustion air blower 14, is passed into the heater proper 20 where the ventilating air circulates over a heat exchanger 22 and leaves the heater at an appropriate opening 24 so as to pass into the space to be heated. Within the heater, the combustion air is mixed with a gaseous fuel delivered through a pipe 24 and this mixture is ignited by a spark plug 26 which receives its energy from an ignition transformer 28. Products of combustion, after passing through the heat exchanger 22, are exhausted to the atmosphere remote from the space to be heated through the exhaust pipe 30.

15 By means of a modulating control valve 32, the pressure on the fuel passing through the pipe 24 to the heater varies depending upon the rate of combustion air flow from the blower 14. This is accomplished by means of a static pressure tap 34 connected to the combustion air conduit and a low pressure tap 36 connected to the throat of a venturi 38 located in the same conduit. It is apparent that these connections are such that the greater the rate of flow of combustion air, 20 the greater the pressure differential existing between the taps 34 and 36. This pressure difference is communicated to the valve 32 and as is explained in the previously referred to copending application of Frank A. Ryder, this pressure acts to vary the pressure upon the fuel supplied to the heater, such that the mixture ratio in the heater is kept comparatively constant regardless 25 of the rate of flow of combustion air. Thus, the heat output of the heater depends upon the voltage across the variable speed motor 10. The higher this voltage, the higher the speed of rotation of the motor and blowers, and thus the greater the heat output. The converse is, of course, also true.

30 The control arrangement particularly adapted, but not limited, to use with a heater of this type and which forms the subject matter of the present invention comprises a heat motor 40 made up of a cylindrical container 42 having an inturned annular flange 44 at its open end sealed to the open end of a corrugated metal bellows 46. At its upper or opposite end, the container wall is spaced from the closed end 48 of the bellows sufficiently to provide room for an electric heating element 50. The space within the container 42 and around the bellows 46 is filled with a liquid which expands when heated. Acetone has been found satisfactory for this purpose.

35 At its upper end 48, the inside surface of the bellows is connected to a link 52 which extends

out through the open end thereof and is connected by means of a pivot pin 54 with an intermediate point of an arm 56 pivoted at one end to a stationary portion of the structure at 58. The opposite end of this arm is provided with a yoke 60. The spacing from the yoke 60 to the pin 54 is great as compared to the spacing between the points 54 and 56, so that the yoke moves in the same direction as the link 52 but to a considerably greater extent.

The yoke 60 straddles a pin 62 at the end of a variable resistor slider arm 64 pivoted at a point 66 adjacent the pin 62. The opposite end of the arm 64 is equipped with a slider 68 which is in contact with a coil type resistance element 70, one end of which is connected by way of a wire 72 to the blower motor 19, the opposite side of the motor being connected to the power supply by a lead 73. As the slider 68 approaches the high resistance end of the element 70, the lower end in the illustration, a projection 74 upon the slider operates to open a switch 76 electrically connected between the slider arm 64 and the other side of the power supply. Thus, heating the resistance element 50 causes the liquid filling within the container 42 to expand, thereby urging the upper end of the bellows 48 downwardly. This movement, operating through the link 52, swings the arm 56 downwardly around the pivot point 58 so that the yoke 60, by depressing the pin 62, swings the slider 68 toward the end of the resistance element 70 which is connected to the motor, thereby decreasing the resistance of the motor circuit and increasing the speed of the blowers 12 and 14. Whenever the electric heater 50 is de-energized a sufficient length of time to permit the bellows 56 to elongate a predetermined amount, the slider 68 will be swung almost completely to the high resistance end of the resistor 70, at which point the motor 19 is operating at the lowest speed consistent with efficient heater combustion. If under these conditions the heat output of the heating system is still more than is required, the slider 68 will move a slight additional amount, whereupon the projection 74 opens the switch 76, thus interrupting the motor circuit so as to discontinue heater operation until such time as heat is required.

The controller for the electric heating element 50 of the heat motor 49 comprises a bridge circuit made up of fixed resistors A and B which may be identical and are so connected that one end of each is common, as indicated at 80, this end being connected to one end of the heating element 50 by a wire 82. The opposite end 88 of the resistor A is connected to the main line through a rectifier 84 which may be of the well known copper oxide type and which permits electric energy to flow from the line toward the resistance element A but not in the opposite direction. Similarly, the opposite end 90 of resistor B is connected to the other side of the power supply by way of a line 86. From the terminal 90 of resistor B, the line 86 also leads to one end of a resistance element D₁, the other side of this latter resistor being connected by a wire 92 to one end of a fourth resistance element D₂. At its opposite end, resistor D₂ is connected to a wire 94 which leads to a variable resistor C connected on its other side to a line 96 leading to the power supply end 88 of the resistor A. The electric heater 50, previously mentioned as being connected on one side to the lead 82, is connected at its opposite end by a wire 98 to a second rectifier 98, while from the opposite side of the recti-

4
fier a line 100 leads to a point 101 upon the wire 84 which connects resistors D₁ and C.

Of these resistors, A and B are of fixed value and have a low temperature coefficient of resistance. In other words, changes in temperature have little or no appreciable effect upon their resistance. Also, the variable resistor C has a low temperature coefficient of resistivity. On the other hand, the resistors D₁ and D₂ have a high temperature coefficient of resistance, such that an increase in the temperature of these units increases their resistance considerably. The resistance element D₁ is located within a case 102 at some point along the inlet air duct 16. The case is equipped with an air inlet tube 104 which extends into the air duct 16 and has its open end facing upstream. A second tube 106 leads from the case 102 and extends into the duct 16 so as to face downstream therein. Thus, whenever air is flowing through the duct 16, a portion thereof will be diverted into the box 102 so as to circulate around the resistor D₁ and then return to the duct. The resistance element D₁ is, therefore, maintained at the temperature of the air outside of the building to be heated with the result that its resistance increases whenever the outside air temperature increases. The resistor D₂ is positioned within a case 108 located within the room to be heated so that it is maintained at substantially the temperature of the air therein.

Inspection of the circuit just described will disclose that the resistors A, B, and C form three sides of a bridge while the resistors D₁ and D₂ in series form the fourth side. Inasmuch as the resistance of A and B is constant, it follows that whenever the resistance of D₁ and D₂ together is less than the resistance C, the bridge will be unbalanced so as to cause current to flow through the heating element 50. On the other hand, if the resistors D₁ and D₂ together are at a high enough temperature so that their resistance is greater than the resistor C, no current will flow through the heating element 50 because the rectifier 98 prevents current transmission in the reverse direction.

The additional rectifier 98 is used because the circuit is shown as connected to an alternating current source. If a direct current source is used, this rectifier 98 is unnecessary.

When the system is in use, the variable resistor C, which may be located within the same case 108 as the resistor D₂, is adjusted to the temperature desired. If the temperature setting called for is such that the resistance of the portion of the resistor C remaining in circuit is less than the resistors D₁ and D₂ together, no current will flow through the heating element 50. Since the bellows 48 is not heated, it will drop toward room temperature and will expand so as to swing the slider 68 downwardly until the switch 76 has been opened. The heater is, therefore, in the off position.

If, under the above conditions, the temperature within the room drops, or if the temperature outside the space to be heated decreases, the resistance of the elements D₂ or D₁, respectively, will be decreased. Whenever the decrease in the resistance of either becomes sufficient so that the resistance of the two in series is less than that of the resistor C, the bridge becomes unbalanced and current is caused to flow through the heating element 50, thereby raising the temperature of the liquid filling within the case 42 so as to collapse the bellows 48 slightly, with the result that the slider 68 is moved upwardly so as to

close the switch 76 and start the heater. If the temperature of the room is well below a desirable level, or if the temperature outside has dropped considerably, it is apparent that the resistance of the elements D₂ or D₁, or both, will drop sufficiently so that the greater bridge unbalance will cause a greater heating effect in the element 50, thereby causing the slider 68 to move so as to take still more resistance out of the motor circuit and increase the heater output still more.

From the above it is apparent that the bridge circuit always operates to provide heat whenever the temperature of the room is below a satisfactory level and that as the temperature of the room approaches the satisfactory level, the heater is gradually modulated so as to reduce the heat output. It is also apparent that this effect is influenced by the anticipating unit D₁ which is located so that it can sense the temperature of the outside air. Thus, any sudden drop or rise in the outside air temperature causes the heater to produce more or less heat, respectively, even though the temperature within the space to be heated has not changed. This permits the heater to increase the heat output to the room so as to keep up with the increased heat loss from the room to the outside.

If it is desired that the room controller unit D₂ have a more pronounced effect in influencing heater operation than the unit D₁, this can easily be accomplished. For instance, merely by decreasing the resistance of the unit D₁ relative to D₂, so that changes in the temperature of the unit D₂ will have a greater effect upon the total resistance in that leg of the bridge than will changes in the temperature of the resistor D₁, the desired result is achieved.

Although for purposes of illustration I have indicated the motor controller as a variable resistor comprised of the coil 70 and slider 68, it will be appreciated that, if desired, this unit may comprise a variable reactance of the inductive type or may be a variable transformer.

Having described my invention, what I claim as new and useful and desire to secure by Letters Patent of the United States is:

1. In a device of the type described, a motor speed controller, a heat responsive device connected for operation of said controller, an electric heating element for operating said heat responsive device, a first resistor having a high temperature coefficient of resistance and arranged to be sensitive to the temperature of the space to be heated, a second resistor having a high temperature coefficient of resistance arranged to be sensitive to the temperature of the ambient air, a variable resistor having a low temperature coefficient of resistance, said resistors being electrically connected so that both of said resistors having a high temperature coefficient of resistance form one leg of a bridge circuit, said variable resistor forming a second leg of said bridge circuit, other resistors having a low tem-

perature coefficient of resistance forming the other legs of said bridge circuit, circuit means connecting said bridge to a power source and a bridging wire for said bridge containing said heating element, said bridging wire including a rectifier for preventing energization of said heating element by said bridge when said bridge is unbalanced in one direction but for causing continuous energization of said heating element when said bridge is unbalanced in the other direction.

2. In a device of the type described, a variable reactor, an electric heating element, means responsive to the heat output of said heating element for operating said reactor, a pair of resistors each having a high temperature coefficient of resistance, said resistors being connected together and forming one leg of a bridge circuit and being arranged to be sensitive to different temperature conditions, a variable resistor having a low temperature coefficient of resistance forming another leg of said bridge, other circuit elements forming the other leg of said bridge, circuit means connecting said bridge to a power source and a bridging wire for said bridge containing said heating element, said bridging wire including a rectifier for preventing energization of said heating element by said bridge when said bridge is unbalanced in one direction but for causing continuous energization of said heating element when said bridge is unbalanced in the other direction.

3. In a device of the type described, a variable reactor, an electric heating element responsive to an electric current for operating said reactor, a bridge circuit for energizing said current responsive means when said bridge is unbalanced, said bridge including temperature responsive resistors arranged to be sensitive to the temperature of the space to be heated and of the ambient air and a bridging wire containing said electric heating element, and means to prevent current flowing from said bridge to said electric heating element when said bridge is unbalanced in one direction.

ARTHUR R. COLLINS.
